TEXTILE FABRIC

Seroun Kesh, 18982 Ardmore, Detroit, Mich. 48235

Substituted for abandoned design applications Ser. No. 5,257, Ser. No. 5,260, and Ser. No. 5,261, Jan. 3, 1967. This application Jan. 18, 1968, Ser. No. 10,214

Term of patent 14 years

(Cl. D92—1)

The figure is a plan view of a full width of textile fabric showing my new design, the design unit being marked off with dash lines, which unit is repeated in regular succession as indicated beyond the unit boundaries.

This application is a substitute of the disclosures made in my previous applications D. 5,257, D. 5,260, and D. 5,261, each filed Jan. 3, 1967, and now abandoned.

I claim:

The ornamental design for a textile fabric, as shown and described.
